UNITED STATES PATENT OFFICE.

HENRY MANRODT, OF BROOKLYN, NEW YORK.

ROTARY MOTOR.

1,640,716.

Specification of Letters Patent.

Patented Oct. 8, 1912.

Application filed April 1, 1911. Serial No. 618,236.

To all whom it may concern.

Be it known that I, HENRY MANRODT, a citizen of the Empire of Germany, and a resident of Brooklyn, in the county of Kings and State of New York, have invented certain new and useful Improvements in Rotary Motors, of which the following is a specification.

This invention has reference to improvements in rotary motors and pertains particularly to a rotary motor that can be used as an internal combustion engine, steam or water motor and also as a meter for liquids.

The novel motor comprises essentially two parts rotatable one on the other. The one part is a spherical casing resembling a hollow ball of which parallel side end portions have been cut off leaving a spherical central portion. The other part is a rotor with a conforming spherical surface rotatable within the casing. Means are provided on the casing for supporting a central rotor shaft to which an inner casing is secured. From the walls of this casing a number of open cylinders extend to the outer wall of said rotor. Each cylinder has a piston and piston rod whose inner end is linked to a relatively long lever arrangement carrying on its outer end a roll that travels in an irregular groove of a cam which is permanently secured to the outer casing. The transmission of power is effected by means of this cam with irregular groove and the lever arrangement. By the respective curves in the cam groove the pistons are governed which have thus a varying stroke for the various periods of suction, compression, ignition and expulsion. By virtue of this arrangement the crank shaft and all valves and accessories thereto are dispensed with. Packing rings are provided in the outer wall of the rotor with surfaces conforming to the inner spherical surface of the casing. An exhaust device of novel construction is also provided and other advantages are attained, all as will be fully described herein-after with reference to the accompanying drawings in which a rotary motor is illustrated particularly designed for use with explosive gas mixtures and in which:

Figure 1 represents in front view a rotary motor embodying in desirable form the

present improvements. Fig. 2 illustrates same in a rear view. Fig. 3 is a vertical central cross section. Fig. 4 is a section on line 4-4 of Fig. 3 and Fig. 5 is a front view of the can and pivoted lever arrangement.

Similar characters of reference denote like parts in all the figures.

In the drawings 1 represents the spherical casing to the outer ends of which supports 2 are attached. These supports carry bearings 3 in which a shaft 4 is mounted. On one side of the casing somewhat below the center there is a conduit or fuel inlet 5 as shown in Fig. 3. The casing further is provided with two lateral motor supports 6. One or more spark plugs pass through the casing in desirable location. The lower portion of the casing is enlarged to form an exhaust device and air inlets 7 are provided thereon to prevent the piston on its inward stroke from sucking in waste gases and to cleanse the cylinder and exhaust device by inrushing fresh air.

On the shaft there is the inner casing 8 substantially secured thereto preferably by the well known method of shrinking and by pins 9. The front portion of the inner casing is closed by removable plates 10 whereby the working parts are easily accessible. From the outer wall of the inner casing a number of cylinders 11 extend to the outer surface of the rotor integral therewith and preferably all cast in one piece. Any desired number of cylinders may be provided; six for instance are shown in Fig. 3. These cylinders are open at both ends as shown in Figs. 3 and 4 and disposed at predetermined angles. Each cylinder houses a piston 12 provided with the usual packing rings and a piston rod 13 extending inwardly. The inner end of the piston rod is linked to a two-armed lever 14, 15. The arm 14 of this lever is curved and rigidly secured to a pivot 16 in a bearing 17 which is an integral part of the casing 8 as shown in Fig. 4. The pivot 16 is made in one piece with the curved lever arm 15. This curved arm 15 carries on its outer end a roll 18 that travels in the groove of a cam 19. The cam plate 19 is permanently secured to the rear portion of the outer casing 1 as shown in Figs. 1, 2 and 5. Said cam plate has centrally an opening

shown in Fig. 4. Its groove in which the rolls 18 travel is mathematically designed and of rather irregular shape having a concentric portion as shown in Fig. 5 so disposed as to produce a special period of ignition. By virtue of the described arrangement the transmission of power is effected and the piston strokes are governed. Each cylinder and piston is operated independently from the others.

10 The cylinder has on its outside a suitable number of ribs 21 for the purpose of effecting air cooling during the rotation of the motor. These ribs 21 are shown solely on 15 one cylinder in Figs. 3 and 4 and more or less than shown may be provided.

10 The outer spherical surface of the rotor and the inner surface of the spherical casing like the section of a sphere must have the same radius in all directions. For the purpose of effecting a perfect packing between these spherical surfaces packing rings 22 are provided within the outer wall of the rotor. These packing rings 22 are located in concentric grooves in said outer wall around the cylinder openings and the rings are finished on the outside so as to conform to the spherical surfaces. In this way a perfect packing is obtained and the same effect results as from the packing rings of a piston.

15 The exhaust device is located on the right side of the enlarged lower portion of the casing 1. As shown in Fig. 3 the exhaust gases are forced through a tube 23. This tube is surrounded by a larger tube 24 shown to the left in said figure. The gases streaming through the tube 23 under pressure draw the remaining gases emptying into tube 24 out with them. In this manner the exhaust 20 gases are completely removed. If desired the motor may be provided with a water cooling jacket which may be of any approved construction.

25 The operation of the motor is substantially as follows: Assuming that the rotor turns from the left to right in Fig. 3 and that a cylinder with piston passes the conduit or fuel inlet 5 then the explosive fuel mixture is drawn into said cylinder while the piston 30 performs the inward or forward stroke. This is effected by the movement of the roll in the eccentric cam groove. Upon further rotation of said cylinder it reaches a point where the adjoining portion of the outer 35 spherical casing closes off the explosive gas mixture within said cylinder, and upon further rotation the gas mixture is compressed owing to the changed location of the roll in the eccentric cam groove, the piston thus performing its outward or return stroke. When the piston reaches approximately the top center of the motor casing where a spark plug 25 is located the mixture is ignited.

40 The expansion of the gases due to the combustion of the fuel forces the piston to per-

form an inward or forward stroke whereby the piston rod actuates the pivoted lever arrangement and forces the roll against the respective portion of the irregular cam groove, which is so curved that a revolution 70 of the rotor is effected. Upon further rotation of said cylinder with piston another return stroke follows whereby the exhaust gases are forced out through the tubes 23 and 24 of the exhaust device. This cylinder

75 traveling farther reaches a point near the end of the enlarged exhaust space where the piston expels the last traces of the exhaust gases by extending somewhat beyond the cylinder opening. These traces and the fresh 80 air entering through the inlets 7 are expelled by the draft of the outrushing bulk of the waste gases. On continued rotation the cylinder again reaches the fuel inlet 5 whereby the cycle of rotation is completed.

85 The other cylinders perform the same cycle of operations, one after another and the explosions take place in quick succession. It is self-evident that only pure gas mixtures are sucked into the cylinders. A sufficiently 90 long suction takes place without creating a partial vacuum.

95 The compression of the gas mixtures proceeds slowly and without great resistance. The piston then is kept briefly in its position by the roll in the cam groove allowing a complete ignition of the explosive gas mixture before the power stroke begins.

100 Thus the piston has a special period of ignition between the compression period and the power stroke owing to the cam groove arrangement whereby any back pressure is avoided. The explosion causes an immediate action and the transmission mechanism fully utilizes the produced power as it has no dead centers and operates from

105 beginning to end. Side pressure of the piston is avoided because its rod moves nearly in a straight line. The power period may be prolonged at will whereby full use of the great tension of the gases is made, and the 110 cylinders and exhaust devices are perfectly cleansed during each revolution of the motor.

115 Although the described motor presents all the desired advantages I do not limit myself to the particular construction of the details and various changes may be made without departing from the spirit of this invention

120 which is characterized mainly by the rotation of one part on another whose spherical surface portions make it possible to effect a perfect packing by means of the packing rings with conforming surfaces and the use of the cam with eccentric groove which may be specially constructed for motors for various applications. Accordingly various parts

125 may be differently arranged and stationary parts made rotatable and vice versa.

I claim as my invention:

1. A rotary motor comprising essentially a stationary and a rotary part rotatable 130

5 relatively to the other, both parts having spherical surfaces of the same radius in all directions, admission and exhaust ports and spark plugs on the one part, and means for the compression of the explosive fuel on the other part.

10 2. A rotary motor comprising essentially a stationary and a rotary part rotatable relative to the other, both parts having surfaces of the same radius in all directions, admission and exhaust ports and spark plugs on the stationary part, means for the compression of the explosive fuel on the rotary part, and means for the expulsion of the 15 waste gases.

20 3. A rotary motor comprising essentially a stationary casing with spherical inner surface, a rotor within having a corresponding spherical surface sliding on the spherical 25 surface of the casing during rotation, admission and exhaust ports and spark plugs in the casing, means for suction and compression of the explosive fuel in the rotor, and means for the expulsion of the exhaust 30 gases.

35 4. A rotary motor comprising a casing with fuel inlet and having a spherical inner surface, a rotor within with spherical outer surface, a number of open cylinders with 40 pistons and piston rods within the rotor, a stationary cam on the casing having an irregular groove with eccentric sections, and transmission mechanism linked to the piston rod and having an end roll that travels in 45 the cam groove.

50 5. A rotary motor comprising a casing with fuel inlet and having a spherical inner surface, a rotor within with spherical outer surface, a number of open cylinders with 55 pistons and piston rods within the rotor, packing rings with conforming spherical surfaces around the cylinder openings, a stationary cam on the casing having an irregular groove with eccentric sections, and transmission mechanism linked to the piston 60 rod and having an end roll that travels in the groove.

65 6. A rotary motor comprising a casing with fuel inlet and having a spherical inner surface, a rotor within with spherical outer surface, a number of open cylinders with pistons and piston rods within the rotor, packing rings with conforming spherical surfaces around the cylinder openings, a stationary 70 cam on the casing having an irregular groove with a concentric portion, and a lever arrangement linked to each piston rod pivotally secured within the rotor and having an outer end roll traveling in the cam groove, said concentric groove portion of the cam being so disposed as to produce a special period of ignition.

75 7. A rotary explosion motor comprising an outer casing with fuel inlet and having

a spherical inner surface, a rotor within 65 with a spherical outer surface, a suitably supported rotor shaft, a closed inner casing rigidly secured to said shaft, a number of cylinders open at both ends extending from the inner casing to the outer spherical portion of the rotor, a stationary cam on the outer casing with irregular groove having concentric and eccentric sections, and means in connection with the piston rods and the cam groove for effecting the forward and 75 return stroke of the pistons.

80 8. A rotary explosion motor comprising an outer casing with fuel inlet and having a spherical inner surface, a rotor within with a spherical outer surface, a suitably supported rotor shaft, a closed inner casing rigidly secured to said shaft, a number of cylinders open at both ends extending from the inner casing to the outer spherical portion of the rotor, a stationary cam on the 85 outer casing with irregular groove, means in connection with the piston rods and the cam groove for effecting the forward and return stroke of the pistons, means for igniting the fuel, and means for expelling the 90 waste gases both in the outer casing.

95 9. A rotary explosion motor comprising an outer casing with fuel inlet and having a spherical inner surface, a rotor within a spherical outer surface, a suitably supported rotor shaft, a closed inner casing rigidly secured to said shaft, a number of cylinders open at both ends extending from the inner casing to the outer spherical portion of the rotor, concentric packing rings therein with 100 conforming spherical outer surfaces around the cylinder openings, a stationary cam on the outer casing with irregular groove, means in connection with the piston rods and the cam groove for effecting the forward and return stroke of the pistons, 105 means for igniting the fuel, and means for expelling the waste gases both in the outer casing.

110 10. A rotary motor comprising a casing with fuel inlet and having a spherical inner surface, a rotor within with spherical outer surface, a number of cylinders open at both ends with piston and piston rods within the rotor, packing rings with conforming spherical 115 outer surfaces in the outer portion of the rotor around the cylinder openings, a stationary cam with irregular groove on the casing, means in connection with the piston rods and cam groove to effect the forward and return stroke of the piston, a spark plug in the casing, and an exhaust device on the casing consisting of an inner and outer tube and nearby air inlets, so disposed that the bulk of the waste gases is forced through 120 the inner tube and draws air and the last traces of the waste gases through the outer tube.

11. In a rotary motor of the type described, a casing having a spherical inner surface, a rotor within with corresponding spherical outer surface sliding on the spherical inner surface of the casing during the operation of the motor, and split packing rings in the outer portion of the rotor with conforming spherical outer surfaces where-

by a perfect packing of the spherical surfaces is attained.

Signed at New York, N. Y., this 31st day of March, 1911.
